UNITED STATES PATENT OFFICE

PHILIP LANG, OF CEDAR FALLS, IOWA, ASSIGNOR TO WAGNER MANUFACTURING COMPANY, OF CEDAR FALLS, IOWA

DOOR-OPERATING MECHANISM

Application filed February 10, 1925. Serial No. 8,287.

My invention relates to improvements in door operating mechanism.

The object of my invention is to provide a door operating mechanism supported by fluid pressure, and having means whereby the last 5 part of the closing and opening movement of the door is gradually retarded so that the door will not slam.

Another object of my invention is to provide a door operating mechanism in which the fluid pressure is readily controlled by the operator of the elevator to which this invention is more particularly applied, and whereby the door operating mechanism cannot be 10 operated until the car has reached a predetermined point in respect to the door opening.

A further object of my invention is to provide a door operating mechanism of this character which is readily applied to the ordinary 20 elevator door operating mechanism having certain details of structure and combination of parts hereinafter more fully set forth.

In the accompanying drawings:

Figure 1 is a side elevation of the inside 25 of an elevator shaft showing my improved door operating mechanism applied thereto.

Figure 2 is an enlarged side elevation of Figure 1 showing one of the retarding cylinders partly in section.

Figure 3 is a front elevation of Figure 2 30 showing the operating cylinder in section.

Figure 4 is an enlarged transverse sectional view taken on the line 4—4 of Figure 3.

Figure 5 is a diagrammatical view of the 35 elevator shaft and elevator showing the air controlled mechanism for opening and closing the air controlled valve.

Referring now to the drawings, 1 represents a portion of the elevator shaft which is 40 provided with the usual door openings closed by the door 2. This door is of the sliding type and is operated through the medium of the lever 3 pivoted at 4, said lever pivotally connected at 5 to the link 6, which is pivoted 45 between the ears 7, carried by the plate 8, secured to the elevator shaft 1, and thus it will be seen that by throwing the lever 3 downwardly, the joint between the lever and the link 6 is broken. This construction is of an 50 ordinary form and is shown for the purpose

of showing my improved door operating mechanism which may be coupled therewith so that the door can be opened by hand should the fluid pressure be cut off at any time.

The plate 8 has secured thereto the lower cap 9, and the upper cap 10. The lower cap 9 is internally threaded and into which is screwed the fluid pressure cylinder 11, which the cap 10 simply surrounds the upper end of the cylinder and forms a support to prevent the twisting action of the cylinder. The upper end of the cylinder 11 is closed by a cap 12, and extending down through the cap 12 is the piston rod 13 having at its lower end, 60 within the cylinder, the piston 14 provided with any desired packing 15 whereby the escape of fluid from below the piston is prevented. Surrounding the piston rod 13 within the cylinder 11 is a coil spring 16 which has its lower end bearing upon the upper end of the piston 14, and its upper end engaging the cap 12 whereby said spring is normally exerting a downward pressure upon the piston and holding it in its downward position 65 as shown in Figure 3 of the drawings.

The piston rod 13 above the cap 12 is connected to a cross arm 17 which has its inner end provided with laterally extending end 18 entering the grooves 19 in the plate 20 which is riveted or bolted to the plate 8. By this structure it will be seen that the cross head 17 is free to move by the force of the piston 13, and the outer end of the cross head 17 is provided with ears 21 between which is pivoted the link 22, which has its upper end pivotally connected between the ears 23, carried by the link 6. From the foregoing description it will be seen that the upward movement of the piston rod 13 causes the cross head 17 to move upwardly and through the medium of the link 22, the link 6 is moved upwardly on its pivotal connection with the ears 7 and the door opened, and the reverse movement of the piston rod closes the door.

The cap 9 has secured to its lower face the rotary valve casing 24 which has a communication with the lower end of the cylinder, and the rotary valve casing has a valve stem 25 extending outwardly therefrom, and which 100

carries the arm 26 which is pivotally connected at 27 to the upper end of the rod 28. This rod 28 passes through the cap rod casting 29, and surrounding the rod below the casting 29 is a coil spring 30 which normally holds the rod 28 in a downward position so that the rotary valve within the casing 24 is normally held closed so that the fluid pressure will not pass into the cylinder 11. The 10 rotary valve casing 24 is supplied with a fluid pressure pipe 31 for maintaining a fluid pressure within the valve casing so that when the valve is oscillated the fluid pressure will be supplied to the cylinder. The rod 28 is 15 pivoted at 32 to the lever 33, pivoted at 34 to the elevator shaft, and said lever extends inwardly and is provided at its inner end with the roller 35. The elevator is provided with a bell crank lever 36 connected to the rod 37 20 which extends downwardly and is pivotally connected at 38 to the intermediately pivoted lever 39 which is pivoted at 40 to the bracket 41 carried by the elevator. The outer end of the lever 39 is pivotally connected at 42 to 25 the shoe 43, and this shoe 43 has a link connection 44 with a bracket so that, when the rod 37 is moved upwardly the shoe 43 will move outwardly and maintain its vertical position. The ends of the shoe are curved 30 inwardly as indicated at 45 and 46 so that the roller 35 will engage the curved portion 45 of the shoe, and the lever 33 is rocked upon its pivot for forcing the rod 28 upwardly, and opening the valve to admit the fluid pressure 35 to the cylinder 11 below the piston 14.

In order to retard the upward movement of the piston rod 13 near the end of its upward stroke, and also to retard the downward movement of the piston rod near the 40 end of its downward stroke I have provided two dash pots 47 and 48.

The cross head 17 has secured thereto the rod 49 which extends downwardly through a guide 50 carried by the cap 9 and extends 45 down through the cap 51 which is rigidly supported by the plate 8. Pivotally mounted upon the cap 51, by means of the ears 52 is a dash pot 48 carrying a piston 54 having a piston rod 55 connected thereto, and extending 50 outwardly beyond the cylinder and connected to the cross arm 56 carried by the rod 49. By this structure it will be seen that the rod 49 is connected with the piston 54 and the downward movement of the cross head 17 55 caused by the exertion of the spring 16 on the piston 14 is retarded near the end of its downward stroke.

Carried by the member 29 is a piston rod 57 which carries at its lower end the piston 60 which operates in the cylinder 47. The lower end of the rod 49 rigidly carries the arm 59 provided with ears 60 between which the lower end of the cylinder 47 is pivoted. By this structure it will be seen that as the 65 cross head 17 is forced upwardly by the

piston rod 13 through the medium of the fluid pressure, in the cylinder 11, the rod 49 is moved upwardly carrying with it the cylinder or dash pot 47 which is retarded by the piston 58 and is supported by the plate 8. In order to regulate the flow of fluid in both the dash pots 47 and 48 I have provided the by passes 61, and controlled by the needle valves 62, whereby the last part of the movement of the piston 13 is controlled in both directions. 75

When the fluid pressure is released the spring 16 forces the piston 14 downwardly carrying with it the cross head 17 which in turn forces the rod 49 downwardly, and the same carrying the piston 55, and the piston working in the dash pot 48 the last part of the downward movement of the piston is retarded and the door is prevented from slamming when opening or closing. 80

Having thus fully described my invention what I claim is:—

1. The combination with a movable member, of a reciprocating dash pot for retarding the movement of the said member in one direction, and a stationary dash pot for retarding the movement of the said member in the opposite direction. 85

2. The combination with a movable member, of a reciprocating dash pot for retarding the last part of the movement of the said member in one direction, and a stationary dash pot adapted to retard the last part of the movement of the said member in the opposite direction. 90

3. The combination with a movable member, a dash pot connected to the said movable member for retarding the movement thereof in one direction, and a piston connected to the movable member and cooperating with a dash pot for retarding the movement of the member in the opposite direction. 100

4. The combination with a movable member, a dash pot connected to the movable member for cooperating with a stationary piston and retarding the movement of the movable member in one direction, and a piston connected to the movable member and cooperating with a stationary dash pot for retarding the movement of the movable member in the opposite direction. 110

5. The combination with a reciprocating member, a dash pot connected to the reciprocating member for cooperating with a stationary piston for retarding the last part of the movement of the reciprocating member in one direction, and a piston connected to the reciprocating member and cooperating with a stationary dash pot for retarding the last part of the movement of the reciprocating member in the opposite direction. 120

6. The combination with a reciprocating member, a cross head connected to the reciprocating member, and a stationary and movable dash pot cooperating with the cross 125

head for controlling the movement of the reciprocating member in both directions.

7. The combination with a reciprocating member, a cross head connected to the reciprocating member, a movable dash pot connected to the cross head for retarding the movement of the reciprocating member in one direction, and a piston connected to the cross head and cooperating with a stationary dash pot for retarding the movement of the reciprocating member in the opposite direction.

8. The combination with a reciprocating member, a cross head carried by the reciprocating member and two dash pots cooperating with the cross head, one for retarding the movement of the cross head in one direction and the other the movement thereof in the opposite direction.

9. The combination with a reciprocating member a cross head connected thereto, a dash pot connected to the cross head and cooperating with a stationary plunger for retarding the upward movement of the cross head in one direction, and a plunger carried by the cross head, and cooperating with the stationary dash pot for retarding the movement of the cross head in the opposite direction.

10. The combination with a reciprocating member, a cross head connected thereto, a dash pot connected to the cross head and cooperating with the stationary plunger for retarding the upward movement of the cross head in one direction, and a plunger carried by the cross head and cooperating with a stationary dash pot for retarding the movement of the cross head in the opposite direction.

11. The combination with a reciprocating member, a cross head connected to the reciprocating member, a dash pot carried by the cross head and cooperating with a stationary plunger for retarding the upward movement of the piston, and a plunger connected to the cross head and cooperating with a stationary dash pot for retarding the downward movement of the piston.

12. The combination with a reciprocating member, a cross head connected to the reciprocating member, a rod connected to the cross head, a dash pot carried by the rod and cooperating with a stationary plunger for retarding the upward movement of the reciprocating member, and a plunger carried by the rod and cooperating with a stationary dash pot for retarding the last part of the downward movement of the reciprocating member.

60 In testimony whereof, I have signed this specification.

PHILIP LANG.
